DESIGN FOR A DRAWER PULL OR SIMILAR ARTICLE

George A. Johns, New Freedom, Pa., assignor to
American Insulator Corporation, New Freedom,
Pa., a corporation of Delaware

Application February 8, 1940, Serial No. 90,128

Term of patent 3½ years

To all whom it may concern:

Be it known that I, George A. Johns, a citizen of the United States of America, residing at New Freedom, in the county of York and State of Pennsylvania, have invented a new, original, and ornamental Design for a Drawer Pull or Similar Article, of which the following is a specification, reference being had to the accompanying drawings, forming part thereof, wherein

Fig. 1 is a top plan view of the drawer pull or similar article, showing my new design;

Fig. 2 is a bottom plan view thereof;

Fig. 3 is a front view thereof;
Fig. 4 is a rear view thereof;
Fig. 5 is an end view thereof;
Fig. 6 is a vertical transverse sectional view taken on the line 6—6 of Fig. 4; and
Fig. 7 is a vertical transverse sectional view taken on the line 7—7 of Fig. 4.

I claim:

The ornamental design for a drawer pull or similar article, as shown.

GEORGE A. JOHNS.
